(57) **CLAIM**

The ornamental design for a cosmetic jar as shown and described.

DESCRIPTION

FIG. 1 is a perspective view of a cosmetic jar showing our new design;

FIG. 2 is a front view thereof, a rear side view thereof being identical to the front view;

FIG. 3 is a top plan view thereof;

FIG. 4 is a bottom plan view thereof;

FIG. 5 is a right side view thereof, a left side view thereof being identical to the right side view; and,

FIG. 6 is a cross-sectional view thereof taken along line 6-6 in FIG. 2.

The broken lines depict portions of the cosmetic jar that form no part of claimed design. The oblique line shadings represent a portion that is transparent or translucent in the cosmetic jar, and the stipple shadings represent transparency gradient of the portion that is transparent or translucent in the cosmetic jar.
